UNITED STATES PATENT OFFICE

2,687,186

PUMP DRIVING MECHANISM

Carl F. Erikson, White Plains, N. Y., assignor, by
mesne assignments, to Nathan Manufacturing
Corp., a corporation of New York

Application May 5, 1951, Serial No. 224,756

7 Claims. (Cl. 184—27)

1

This invention relates to reciprocating drives such as employed in pumps, and is particularly applicable to multiple force-feed lubricators and the like where separate adjustment of the oil furnished to several different points is desirable. Such lubricators are useful in many places including trucks and other parts of railway equipment, automobiles, etc.

The object of the invention is to provide a mechanism of the kind referred to which will be simple and rugged in construction and low in cost of manufacture, which will admit of easy servicing and which will provide for ready and individual adjustment of the fluid delivered to each of several points.

In the accompanying drawings

Figure 1 shows a side view of a lubricator mechanism embodying my invention, partly in section.

Figure 2 shows a top view of the same lubricator with part of the cover removed and the mechanism within shown partly in section on the line 2—2 of Figure 1, some of the pump units being omitted for clarity.

In this embodiment of the invention the operating mechanism is enclosed within a housing 10 which serves also as a reservoir for a supply of lubricant in which the mechanism is partly immersed. The oil is introduced through a port 11 below which is supported a suitable screen 12 in accordance with known practice.

Within the housing is a detachable frame 13, held in place by bolts or other suitable means and which carries a drive shaft 14 and a pump supporting rod 15. Shaft 14, at one end, extends through the side of the housing as shown in Figure 2, and has clamped thereon an arm 17 which is given a reciprocating motion by any convenient source of power. On railway or other vehicles the arm may be driven by a strap 16 attached to the car axle or truck frame, the housing 10 being located on the car body, (or vice versa), in a manner known to the art. The arm 17 may be adjusted for length as by using one of the alternative holes 18 for the clamping bolt 19, thereby varying the angular movement of shaft 14 for a given travel of the end of the arm 17.

Within the housing, a drive plate 20 is attached to drive shaft 14 so as to extend laterally therefrom and vibrate up and down about the axis of shaft 14 as the latter oscillates. In the form here shown the plate is biased to its upper position by a tension spring 21 attached at one end to the frame 13 and at the other end to a spur 22 ex-

2

tending laterally from the shaft 14. 23 is a stop secured to the shaft and adapted to bring it up against the frame to prevent excessive rotation of the shaft while making repairs or adjustments.

5 The pump units 25 are mounted for individual angular adjustment on the supporting rod 15. For purposes of clarity only three of these units are shown on the drawing but there may be any desired number. Each pump unit comprises a body 26 suitably formed for mounting on rod 15, and provided with a bore 27 constituting the pump cylinder. The bottom of the bore is closed by an inlet valve 28, here shown as a ball valve of a known type. The outlet valve 30 is located 10 in a bore 31 in body 26 extending laterally from the power part of the cylinder bore. This valve is preferably a spring pressed rubber disc valve which gives a somewhat better seal for such a location.

20 Piston 33 for the pump cylinder has an extension 34 passing through a guide opening 35 in a transverse section of guide arm 36 which rises from body 26 generally parallel to said extension 34. Compression spring 37 surrounding the lower 15 part of extension 34 tends to keep the piston in its outer position and with the end of the extension adjacent to or in contact with, drive plate 20.

25 A flexible coupling link 39 leads from the outlet valve of each pump unit to one of a number of oil feed terminals 40 secured in one wall of the housing 10. From these terminals oil ducts to the several points to be lubricated are provided in the usual manner. The flexible links permit the angular movements of the pump units which 30 are necessary for the stroke adjustment herein- 35 after referred to.

30 A series of stroke adjusting screws 42—42, one 40 for each pump unit, is provided in the wall of the housing adjacent to the pump units. These screws extend through nuts secured to the wall of the housing, the outer ends being accessible for adjustment and the inner ends positioned to bear against the respective guide arms 36 of the several pump units. Each pump unit is provided 45 with a spring 44 attached at one end to a convenient point, as at 45, on the pump body and at the other end to a point on the frame 13, and serving to keep the guide arm 36 of its pump pressed against the adjusting screw 42 of that pump unit. A rod 46 extending across the frame 13 may conveniently be used for the point of attachment thereto of all the springs 44. A readily 50 detachable cover 48 may be provided for the outer ends of adjusting screws 42—42 to protect 55

them from damage, dirt or accidental misadjustment.

In operation, the driving lever moves angularly up and down under the influence of the strap 16 and the spring 21 as the result of the constant change in distance between the vehicle body and the unsprung part to which the strap may be attached; or as the result of the application of power from any other convenient source. This imparts a like motion to the driving plate 20, causing the several pump pistons to reciprocate in their respective cylinders under the combined effect of the several springs 37 and the driving plate 20, thus forcing oil from the supply in the housing to the several points to be lubricated by way of the respective flexible couplings 39.

If observation shows that too much oil is being furnished to any particular point, the adjusting screw 42 for the pump supplying that point is turned to force the piston extension 34 of that pump toward the axis of vibration of the plate 20 thus shortening the travel of the piston. If the oil supply is inadequate, the screw 42 is turned in the opposite direction. Thus by separate adjustment of the several screws 42, each point can be supplied with the correct lubrication.

In case the total supply is too much or too little, the arm 17 may be adjusted on the shaft 14 to give a larger or smaller angular movement to the plate 20.

It will be understood that the particular construction shown is intended to be illustrative only and is not to be taken as limiting the invention except as indicated in the appended claims.

What I claim as new is:

1. A multiple forced feed lubricator having a housing acting as an oil reservoir and pump mechanism within said housing comprising, a detachable frame carrying an oscillating drive shaft and a cylinder supporting rod, a plurality of pump units mounted for independent angular adjustment on said rod, a vibrating drive plate attached to said drive shaft and extending laterally therefrom to overlie said pump units, an extension on each pump piston having operating relation with said plate, a resilient means individual to each pump unit tending to move its piston extension toward the edge of the plate remote from the drive shaft, and a stroke adjusting means for each pump unit for holding its piston extension at any selected distance from the drive shaft.

2. A lubricator in accordance with claim 1 having an operating mechanism for the drive shaft provided with means for adjusting the degree of oscillation of said shaft.

3. A lubricator in accordance with claim 1 in which each pump has a flexible link connecting it with a corresponding outlet on the housing body.

4. In a device of the kind described, a plural-

ity of pump units each having a piston with a piston rod extending therefrom, said units being arranged side by side and supported for individual angular adjustment with respect to one another, a resilient means for each pump unit tending to hold the piston of its unit in its outer position, a single drive plate for said pump units supported for angular movement and overlying said pump pistons for moving them to their inner positions by making a contact with the several piston rods, and mechanism individual to each pump unit for varying at will the distance between the axis of angular movement of said plate and the point at which it makes contact with the pump's piston rod.

5. A device in accordance with claim 4 wherein there is also means for varying the angular movement of said plate.

6. In a device of the kind described, a plurality of separate cylinders, pistons therein each having an exterior extension for moving it, valve mechanism for each cylinder for causing the transfer of fluid from one place to another upon reciprocation of the piston, a pivotally supported vibrating driving plate for driving said pistons having a surface making contact with said piston extensions, said contact points being movable toward or from the pivot of said plate to vary the stroke imparted to said extensions according to the distance of each extension from said pivot, and means for independently varying the point of contact of each piston extension with said driving plate.

7. In a device of the kind described, a plurality of separate cylinders, pistons therein each having an exterior extension for moving it, valve mechanism for each cylinder for causing the transfer of fluid from one place to another upon reciprocation of the piston, a pivotally supported vibrating driving plate for driving said pistons having a surface making contact with said piston extensions, said contact points being movable toward or from the pivot of said plate to vary the stroke imparted to said extensions according to the distance of each extension from said pivot, means for independently moving the point of contact of each piston extension to a desired distance from said pivot, and driving means for said driving plate having an adjustable connection to the pivot of the driving plate whereby the extent of the vibration of said plate may be varied.
